UNITED STATES PATENT OFFICE

ROY E. TILLES, OF NEW ROCHELLE, NEW YORK

HOSIERY

Application filed April 16, 1931. Serial No. 530,601.

This invention relates to stockings such as those made of delicate fibre and usually knit or looped on certain machines known in the art.

5 The invention is particularly adapted for, and in the present instance is applied to full fashioned stockings made of silk. The object of my invention is to provide a stocking, the more sheer main portion of which is 10 knit or looped in the usual way, but the upper portion of which is a stronger or reinforced material made of heavier threads than the main portion of the stocking. This reinforced or strengthened portion of 15 the stocking is referred to in the trade as the "welt."

On the accompanying drawings, Fig. 1 is a plan view of a complete stocking. Fig. 2 is a similar enlarged view of the upper portion thereof, and Fig. 3 is a similar view to Fig. 2, but showing the upper portion of the stocking folded upon itself.

Referring to the drawings, the numeral 1 indicates the main portion or leg of the 25 stocking, and the numeral 2 the foot portion thereof. The reinforced portion extends from the point 3 to the point 4. The upper edge of the stocking, at 4, is usually finished in a somewhat zig-zag or irregular 30 form known to the art. Immediately below this edge 4 is a doubled portion of the stocking, indicated by the line 5. The joint between this doubled portion and the lower portion of the stocking is knit together when 35 the stocking is manufactured.

Below the doubled portion, terminating at 5, and in the welt, terminating at 3, are a series of transverse lines of small openings or perforations formed in the process of 40 knitting by cross looping or the lateral transfer of the loops by a special action of the knitting machine. These cross loops forming perforations, cause the heavy material of the stocking to be somewhat more 45 flexible at such points. This enables the wearer of the stocking to fold the stocking over on such cross stitches or perforations, so that the length of the stocking may be 50 made to accommodate different lengths of legs of the wearers.

Fig. 3 of the drawings indicates a stocking of the form shown in Figs. 1 and 2 applied to the leg of the wearer, the top or reinforced portion being folded down as indicated at the point 7. The stocking in 55 such instances is usually retained in place by the use of a garter, as indicated by dotted lines at 8. It will thus be seen that a band garter may be placed between any two of the transverse looped or perforated portions 6, the fold coming immediately above the upper edge of the garter and producing a more finished appearance of the stocking at that point than would be the case where the plain fabric of the reinforced portion 60 is folded over the garter.

Another advantage of the construction above referred to resides in the fact that the garter is in some instances likely to produce runs in the knit fabric of the 70 stocking structure. In the present instance, when a clasp garter is attached between the two rows of the cross looped stitches, the run is prevented from traveling downward beyond such stitches; whereas, in the case of the omission of such 75 stitches, the run would continue down the leg of the stocking. It will thus be appreciated that I have produced a structure in a stocking fabric which reduces the possibility of runs to a minimum, at or beyond the point where the garter is applied.

A further advantage of the above structure resides in the fact that when a stocking of the type described is placed in a box 80 or other container for display and sales purposes, the top of the stocking may be folded on one of the lines of transverse stitches, thus giving the stocking a finished appearance when the upper part is folded beneath the adjacent part. This effect 85 would not be produced when the stocking is provided with a welt or reinforced portion not containing the cross or transversely 90 looped stitches.

It will be appreciated from the above description and after a consideration of the drawings, that the embodiment of my invention is not limited to the precise number 95 of cross or looped stitches in the welt por- 100

tion of the stocking, but the number of such rows of stitches or loops may be such as to comply with the preference and demand of the purchasers.

5 Having thus described this form of my invention, what I claim and desire to protect by Letters Patent is:

1. In a full fashioned stocking of delicate material, such as silk and adapted to 10 be folded to accommodate legs of different lengths, and having adjacent the top thereof a welt of heavier reinforced material, the improvement which comprises providing the welt which is extended downward 15 a distance at least greater than the width of the stocking at its open end, and providing such welt portion with a plurality of spaced rows of laterally transferred loops forming transverse lines of openwork 20 whereby the stocking is adapted to be folded downward so that the fold occurs upon and about one of the upper rows of open work to conform the stocking to varying length of leg.
- 25 2. In a full fashioned stocking having the main portion thereof of sheer and delicate material such as silk and adapted to be folded to accommodate legs of different lengths, and having a welt of reinforced 30 or heavier fabric than said main portion, the improvement which comprises having the welt extended downward to accommodate a plurality of transverse bands of said reinforced fabric of substantial width, and provided with a plurality of rows of laterally transferred loops forming lines of open work defining said bands, each of said laterally transferred rows of loops forming a stop to prevent runs below points at which 35 40 a garter may be applied to any one of said bands.

Signed this 11th day of April, 1931.
ROY E. TILLES.
